(57) CLAIM

The ornamental design for an eyelash curler, as shown and described.

DESCRIPTION

FIG. 1 is a top plan view of the eyelash curler according to my new design.

FIG. 2 is a bottom plan view thereof.

FIG. 3 is a right side elevational view thereof, the left side elevational view being a mirror image.

FIG. 4 is a front elevational view thereof.

FIG. 5 is a rear elevational view thereof; and,

FIG. 6 is a perspective view from the curling bowl.
